(57) **CLAIM**

The ornamental design for a band-supported architectural covering, as shown and described.

DESCRIPTION

FIG. 1 is a perspective view of the band-supported architectural covering.

FIG. 2 is a front view of the band-supported architectural covering illustrated in FIG. 1.

FIG. 3 is a rear view of the band-supported architectural covering illustrated in FIG. 1.

FIG. 4 is a first side view of the band-supported architectural covering illustrated in FIG. 1.

FIG. 5 is a second side view of the band-supported architectural covering illustrated in FIG. 1.

FIG. 6 is a top view of the band-supported architectural covering illustrated in FIG. 1; and,

FIG. 7 is a bottom view of the band-supported architectural covering illustrated in FIG. 1.

The dashed or broken lines contained within the figures represent portions of the disclosed band-supported architectural covering that form no part of the claimed design.

The break lines contained within the figures (and the portions of the band-supported architectural covering extending between the break lines) form no part of the claimed design.

1 Claim, 5 Drawing Sheets
